Primary Examiner—Louis S. Zarfas*Assistant Examiner*—Monica A. Weingart*Attorney, Agent, or Firm*—Dowrey & Associates**[57]****CLAIM**

The ornamental design for cartridge magazine floor plate, as shown and described.

DESCRIPTION

FIG. 1 is a top perspective view of a cartridge magazine floor plate with a handgun grip shown in broken line;

FIG. 2 is a top plan view thereof;

FIG. 3 is a bottom plan view thereof;

FIG. 4 is a right side elevational view, the left side elevational view being a mirror image thereof;

FIG. 5 is a front elevational view thereof; and,

FIG. 6 is a rear elevational view thereof.

The broken line showing of the handgun grip is for illustration purposes only and forms no part of the claimed design.
